UNITED STATES PATENT OFFICE.

RUSSELL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

PRESSER-FOOT FOR OVERSEAMING-MACHINES.

No. 875,640.

Specification of Letters Patent.

Patented Dec. 31, 1907.

Application filed February 6, 1906. Serial No. 299,605.

To all whom it may concern:

Be it known that I, RUSSELL G. WOODWARD, a citizen of the United States, residing at Waukegan, in the county of Lake, State of Illinois, have invented certain new and useful Improvements in Presser - Feet for Overseaming-Machines, of which the following is a description, reference being had to the accompanying drawing, and to the letters and figures of reference marked thereon.

My invention relates to sewing machines, and particularly to overseaming machines of the type employing a looper which carries a thread up over the edge of the fabric in position to be engaged by the needle in its descent.

As herein shown, the invention is applied to a Union Special type of overseamer, but it will be understood that I do not wish to be limited to such application. Such a machine embodies a vertically reciprocating needle, a loop spreader which seizes a loop of needle thread below the cloth plate and carries it out beyond the edge of the cloth plate in such position that a looper passing from below up over the edge of the cloth plate will go through the needle loop and carry its own thread into position to be engaged by the needle in its next descent. The presser foot used on such machines is provided with a tongue over which the stitches are formed.

It has been found in practice that when greater than a certain limit of thickness of goods is to be sewed on the machine, that the raising of the presser foot under such increased thickness will cause the looper in its upward movement to strike the tongue on the presser foot and hinder or stop the operation of the machine or possibly break or bend the loops.

I have provided a remedy for the accidental engagement of the looper with the presser foot tongue by notching the latter to allow the looper to clear it even under a maximum thickness of material. I found, however, that a mere clearance notch would not always suffice for although it would enable the looper to clear the tongue, the thread of the looper was apt to catch on the wall of the notch, and thus prevent the thread feeding off the tongue onto the goods to form the stitch.

The object of my invention is, therefore, to provide such a construction as will obviate these defects.

The invention, therefore, consists in the matters hereinafter described and referred to in the appended claims.

The invention is herein shown as applied to the type of machine above referred to, such as shown for example in the application filed by Lansing Onderdonk and myself, November 9th, 1901, Serial No. 81,772, or by Lansing Onderdonk, Serial No. 218,192.

The invention is illustrated in the accompanying drawings, in which,

Figure 1 is a top plan perspective view of a presser foot embodying my invention; Fig. 2 is a perspective view, showing the stitch-forming elements in proper relation when the needle is just beginning to raise to throw out the loop, the spreader just about engaging the needle loop and the looper moving backward; and Fig. 3 is a similar view showing the parts in reversed position.

In these drawings, *n* represents the needle; *s* the spreader and *l* the looper, these parts being of usual construction and operating in the usual manner. The presser foot as a whole is marked *p* and is supported in the usual manner. It is formed with a cut out portion and a plate *a* is secured thereto, having a tongue *t* over which the stitches are formed, this tongue lying along one side the needle and its rear end extending beneath the body portion of the presser foot adjacent thereto. The tongue *t* carried by the plate *a* has a shank portion *b* raised above the body of the plate and has a beveled notch *c*, which permits the looper to clear the foot and tongue even when the presser foot has been raised by a maximum thickness of goods under it, this notch affording a clearance for the looper.

To prevent the looper thread from catching in the notch and breaking, or piling up on the tongue and not slipping off the same properly, this notch must be so constructed as that the looper thread will not engage the notch and hold therein, but slip over the top thereof, and to accomplish this result the walls of the notch are formed on a curved flare, and the top surface of the shank of the tongue adjacent the notch is flat and by reason of the beveled curvature of the walls of the notch, if the thread is laid in said notch by the looper will immediately be drawn out of it in the tightening of the thread, and slip down onto the tongue.

If the thread were drawn straight from the needle across the tongue, it would be very liable to catch therein, and it would be difficult to get it out. The flare between the left hand side of the tongue and the presser foot body, forces the thread along on the tongue as it is drawn taut, and this has the effect of drawing it out of the V-shaped slot. Were it not for the fact that the left hand side of the tongue of the presser foot is made upon the peculiar curve starting at a point opposite the needle, the thread would catch in the V-shaped slot, and would not come out, but the drawing of the thread over a point higher than the sides of the V slot has the effect of keeping it from catching there, and at the same time, allows the looper in its travel to pass over the side of the presser foot, without engaging with it.

It will be understood that I do not wish to be limited to the exact details of construction, the essentials of the invention being that the presser foot has the notched tongue, or the notch adjacent the tongue, so that the looper has sufficient clearance over the presser foot under any desired thickness of goods; and also that the notch is so formed that the thread will not catch in the notch but will slip over it onto the tongue.

Having thus described my invention, what I claim as new and desire to secure by Letters Patent, is:—

1. In a sewing machine having stitch forming mechanism including a device for laying a thread upon the upper surface of the fabric, a presser foot having a recess located in the path of travel of said thread laying device, and upon the top side of the bearing surface of said foot, said recess being so arranged as that the thread will be deflected out of it; substantially as described.

2. In a sewing machine having stitch forming mechanism including a device for laying a thread upon the upper surface of the fabric, a presser foot having a tongue over which the stitches pass and provided with a recess on the top side of its bearing surface, said recess being located in the path of travel of said thread laying device; substantially as described.

3. In a sewing machine having stitch forming mechanism, including a device for laying a thread upon the upper surface of the fabric, a presser foot having a tongue over which the stitches pass and having a shank portion raised above the presser foot

and provided with a recess on the top side of its bearing surface, and being located in the path of travel of said thread-laying device; substantially as described.

4. In a sewing machine having stitch forming mechanism, including a device for laying a thread on the upper surface of the fabric, a presser foot, a plate secured thereto having a tongue provided with a recess on the top of its bearing surface, said recess being located in the path of said thread-laying device; substantially as described.

5. In a sewing machine having stitch-forming mechanism; including a device for carrying the thread over the edge of the presser foot, a needle, a presser foot having a tongue, a notch or recess in said presser foot located in the path of said thread-carrying device, and in advance of said needle, whereby the thread carried by the thread-carrying device is drawn at an angle to the line of feed and deflected upon said tongue; substantially as described.

6. In an overseaming machine having stitch-forming mechanism including a device for laying a thread upon the surface of the fabric, a presser foot provided with a notch or recess to allow for clearance for the said device, said notch or recess having walls to deflect the thread; substantially as described.

7. In a sewing machine having stitch forming mechanism including a device for laying the thread upon the surface of the fabric, a presser foot having a tongue and provided also with a notch or recess to allow for clearance for said thread laying device, said notch or recess having walls to deflect the thread out of the same and on to the tongue; substantially as described.

8. A sewing machine having stitch forming mechanism including a device for laying the thread upon the surface of the fabric, a presser foot, provided with a notch or recess to allow for clearance of the said device, said notch or recess having walls to deflect the thread and said presser foot having a tongue the shank of which is curved as shown; substantially as described.

In testimony whereof I affix my signature, in presence of two witnesses.

RUSSEL G. WOODWARD.
